Published under the Second Trial Voluntary Protest
Program on Mar. 16, 1976, as document No. B502,381

FIG. 1 is a top, rear, and right side perspective view of a clip-on level for portable electric drills showing my new design;

FIG. 2 is a right side elevational view thereof, the left side being a mirror image thereto;

FIG. 3 is a top plan view thereof;

FIG. 4 is a rear elevational view thereof, the front being a mirror image thereto with the spirit tube omitted; and

FIG. 5 is a bottom plan view thereof.

I claim:

The ornamental design for a clip-on level for portable electric drills, substantially as shown and described.
